UNITED STATES PATENT OFFICE.

HENRI GALOPIN, OF MELBOURNE, AND JAMES EVANS, OF AUBURN,
VICTORIA.

INCANDESCENT GAS-BURNER.

SPECIFICATION forming part of Letters Patent No. 354,977, dated December 28, 1886.

Application filed November 12, 1885. Serial No. 182,529. (No model.) Patented in Victoria August 17, 1885, No. 4,182; in Queensland September 13, 1885, No. 45; in South Australia September 28, 1885, No. 606; in Tasmania September 30, 1885, No. 372; in New Zealand October 9, 1885, No. 1,581, and in New South Wales December 2, 1885.

To all whom it may concern:

Be it known that we, HENRI GALOPIN, a citizen of the Republic of France, residing at Melbourne, in the British Colony of Victoria, and JAMES EVANS, a subject of the Queen of Great Britain, residing at Burwood Road, Auburn, in the said Colony of Victoria, have invented an Improved Incandescent Burner for Burning Atmospheric Air Charged with Hydrocarbon Vapors, (for which Letters Patent have been granted in Victoria, No. 4,182, dated August 17, 1885; in South Australia, No. 606, dated September 28, 1885; in Tasmania, No. 372, dated September 30, 1885; in New Zealand, No. 1,581, dated October 9, 1885; in New South Wales, dated December 2, 1885, unnumbered, and in Queensland, No. 45, dated September 13, 1885,) of which the following is a full, clear, and exact description.

Our invention has been designed for the purpose of obtaining a better light than can otherwise be obtained from the combustion of atmospheric air charged with hydrocarbon vapors; and it consists in a peculiar construction of burner, and in the arrangement of parts connected therewith, substantially as herein-after described.

The invention further consists in means whereby the devices may be made self-lighting, so that by simply turning on the gas-supply the gas at the main burner will be relighted, substantially as hereinafter set forth.

Referring to the drawings, Figure 1 is a detached vertical sectional elevation of the incandescent burner, burner-pipe, gas-holder, and gas-supply pipe, showing a pilot-burner in said burner-pipe, whereby the device is made self-igniting. Fig. 2 is a detached elevation of the plug of the stop-cock C on an enlarged scale. Fig. 3 is a section on line xx of Fig. 2. Fig. 4 is a vertical section, on an enlarged scale, through the incandescent burner, illustrating the construction of the latter. Fig. 5 shows a portion of the double-wire fabric employed in the construction of the incandescent burner.

In the above drawings, J indicates the gas-supply pipe provided with a stop-cock, J⁵,

and connected with one end of a gas holder or reservoir, J', to the other end of which is secured a tapering tube, J², in which are arranged one or more perforated diaphragms or wire-gauze partitions, J³, to prevent the flame from the burner being communicated to the gas in the reservoir J'. In this tube J² is fitted a burner-tube, K, that is made tapering outwardly, and carries at its enlarged outer end a burner constructed of a material capable of being brought to incandescence. This burner K' is made of platinum wire-gauze, and preferably of two thicknesses of gauze, k k', so arranged that the meshes of the inner layer, k, will intersect those of the outer layer, k', thereby reducing the size of the meshes correspondingly, and consequently the orifices through which the gas would otherwise escape too freely, all as more plainly shown in Figs. 4 and 5.

The burner K' is constructed in the form of a conical basket, as shown, and forms in its interior a gas-chamber into which gas from the reservoir J' flows, and where it is ignited to bring the basket to a state of incandescence.

By means of the described construction, the gas supplied to reservoir J' is highly heated by the heat generated at the burner, said reservoir being in sufficiently close proximity to said burner to effect this preheating, and as the gas reaches the open-work burner in a highly-heated state is there ignited and combines with atmospheric air to produce an intense heat that rapidly brings the burner to a state of incandescence, a brilliant light without flame being thus obtained.

The described illuminating device may be made self-igniting by applying a pilot-burner, J⁴, to the upper small end of the burner-tube K, as shown in Fig. 1. In this construction we apply a stop-cock, C, to the pipe J², so constructed as to allow, when closed, sufficient gas to pass through to keep a light at the pilot-burner without unduly heating the tube, so that when the gas is fully turned on it will not require to be lit. To this end the stop-cock has a peripheral groove extending half around the same from the main pas-

sage thereof, as plainly shown in Figs. 2 and 3. By means of this construction we obtain a self-igniting light, and the operation of the devices is substantially the same as when the pilot-burner is not employed, except that the gas passing through the burner-tube is further heated by the flame at the pilot-burner, and results in a more thorough or complete combustion, and consequently a more brilliant light. When it is desired to extinguish the light, whether the pilot-burner is used or not, the cock J^5 is turned to cut off the supply of gas to the reservoir J' .

We are aware of United States Patent granted to C. Clamond, No. 261,529, under date of July 25, 1882, and also of British Patent No. 1,403 of 1882; but the constructions therein shown and described are not sought to be claimed in this application, and our invention differs from those shown in the patents referred to in that we make our burner self-igniting on the one hand, and on the other we provide a platinum burner that will last longer than a like burner made of a single layer of fabric; nor is it as liable to become coated with carbon when the flow of gas is low, and thereby obstruct the mesh of the fabric and impair its incandescent properties. Further than this, we are enabled to employ a fabric of compar-

atively coarse mesh, and reduce the size of the mesh by the arrangement of two layers of such fabric, as described; and, lastly, by this arrangement of burner we provide a light-radiating surface nearly twice as great as that obtained by a single layer of fabric.

Having now described our invention, what we claim, and desire to secure by Letters Patent, is—

The herein-described incandescent burner, consisting of the gas-holder J' , the tapering pipe J^2 , connected therewith and provided with a stop-cock, C, having a groove formed in one-half of its perimeter, the ends of which groove merge into the transverse aperture of said stop-cock, and the gauze diaphragms J^3 J^4 , interposed in pipe J^2 , below the stop-cock C, in combination with the tapering burner-pipe K, carrying at the smaller end within the pipe J^2 a pilot-burner, J^4 , and at its wider end a burner, K', composed of two layers of platinum wire-gauze, the meshes of which intersect one another, substantially as described, for the purpose specified.

HENRI GALOPIN.
JAMES EVANS.
